PIPE HANGER

Madden T. Works, Houston, Tex., assignor to
Cameron Iron Works, Houston, Tex.

Application June 7, 1938, Serial No. 212,240

3 Claims. (Cl. 285—22)

The invention relates to a pipe hanger and particularly a hanger of a type which may be lowered through some of the well head fittings and supported in position where it may be sealed and retained against displacement.

In completing a well, particularly where higher pressures are present at the well head, it is desirable to support and seal the tubing string in the well and to remove some of the larger fittings which are thereafter unnecessary and the present pipe hanger has been devised with the view of supporting the tubing and anchoring the tubing in position irrespective of its exact location relative to the supporting structure.

15 It is one of the objects of the invention to provide a pair of seal rings, one on the supporting structure and one on a tubing hanger, which rings may be engaged either independently or simultaneously by a hold-down member which is anchored to the support and by which pressure is applied to the hanger to anchor it in position and form a seal thereabout.

Another object of the invention is to provide a tubing hanger which may be lowered into position through the well head fittings and anchored in sealing position after the fittings have been removed.

Another object of the invention is to provide a sealing assembly for well heads, wherein a seal is formed by a hold-down member with a pipe hanger in such a manner that additional pressure applied to the hanger will permit the hold-down member to also seal with the supporting structure.

35 Another object of the invention is to provide a pair of independent seal rings, one on the well head and one on the pipe hanger, both of which will be engaged by a hold-down head.

Still another object of the invention is to provide a sealing assembly for well heads wherein a seal may be formed with either the tubing hanger or the well head as desired.

Still another object of the invention is to resiliently support a pipe hanger in position so that additional pressure applied thereto will tend to form a seal to confine the pressure within the pipe supported by the hanger and to also form a seal about the hanger to prevent the escape of pressure around the hanger.

50 Other and further objects of the invention will be readily apparent when the following description is considered in connection with the accompanying drawings, wherein:

Fig. 1 is a side elevation of a well head to which the invention is being applied.

Fig. 2 is an enlarged detailed view of the hanger with the hold-down cap being moved to clamp the hanger in position.

In Fig. 1 the well casing is indicated generally at 2 and is surmounted by a casing head 3 which is here illustrated as having a flange 4 thereon. With equipment of this sort it is usual to provide various types of closure devices upon the well head during the drilling operation and in some instances these remain on the well after production is had, while in other instances these closure devices are removed and the Christmas tree fittings applied directly to the well head.

In Fig. 1 a blowout preventer 5 has been shown as disposed upon the well head 3 and is of the type 15 having movable ram members 6 which will close around the string of pipe 7 disposed in the passage 8 of the well bore.

The upper end of this blowout preventer 5 is provided with a seat 10 which is disposed inside 20 of the flange 11 and is arranged to receive a support ring 12. Disposed on the ring 12 is a body of packing 15 of any desired type, which is in turn arranged to be confined by a pipe hanger 17. This hanger is formed with an outwardly extending flange 18 and a downwardly projecting skirt 19. The skirt may be threaded as desired at 20 in order to receive the pipe 7 and support it in position. The upper end of the hanger may be threaded at 22 to receive a continuation 23 of the 30 pipe 7 or this pipe 23 may in some instances be a setting nipple or pipe by which the pipe hanger is set or located upon the seat 10. A snap ring 24 on the skirt 19 holds the support ring 12 thereon until the hanger is positioned on the seat 10. 35

Disposed on the flange 11 is a drilling or gate valve 30 having a flange 31 which is clamped to the flange 11 by a series of bolts 32. A seal ring 33 is clamped between the flanges 11 and 31 by the bolts 32 and is arranged to project into the 40 groove 34 in the flange 11 and the groove 35 in the flange 31. In this manner a seal is formed about the well bore 8 so that there may be no leakage between the flanges.

It will be understood that the blowout preventer 45 5 may be closed about the pipe 7 to cut off the flow of pressure while this hanger is being located. It will also be understood that the blowout preventer 5 had previously been used to close the well bore 8 when the drill stem or other string of 50 pipe was disposed therein, and that during this previous period if there was no pipe in the well and it was desired to close the passage, then of course the gate valve 30 would be closed to cut off the flow of fluid through the well bore. 55

There are many different conditions and sets of circumstances in completing a well bore which determine whether or not some of the equipment may be removed or whether it must remain on the well but it is of course desirable to remove as much of this equipment as possible because of the cost thereof.

With the hook-up shown in Fig. 1 the apparatus has been arranged so that the drilling valve 30 may be removed while the blowout preventer 5 will remain on the well. In other circumstances both the valve and the preventer may be removed and the pipe hanger positioned within the well head 3 and inside of the flange 4, it being the object of the present invention to provide a set of equipment wherein the hanger may be located at the desired elevation and certain portions of the equipment removed.

In Fig. 1 if the pipe 23 is a setting nipple, it will be unscrewed and the valve 30 removed. Before the well is completed however it is desirable to anchor the pipe hanger 17 firmly in position to prevent its displacement. Fig. 2 shows the structure for anchoring and clamping this pipe hanger. In connection with Fig. 2 the construction will be the same regardless of whether the valve 30 is removed or both the valve and the blowout preventer are removed and this Fig. 2 illustrates broadly the idea of a hold-down member 40 which may be applied to any one of the flanges 4, 11 or 31, as the circumstances may require. For purposes of illustration it will be considered that the supporting flange in Fig. 2 is the flange 11 of the blowout preventer 5. The detailed parts thereof have been previously pointed out except for the provision of a groove 42 in the top face of the hanger 17. This groove 42 is arranged to receive a hanger seal ring 43 which projects into a groove 44 in the hold-down member or cap 40. A groove 45 is also disposed in the lower face 46 of the hold-down member 40 in such a position that it will engage the seal ring 33 which is disposed in the groove 34.

As seen in Fig. 2 the bolts 32 have not been drawn down as tightly as possible but have been drawn down sufficiently to bring the cap member 40 against the hanger seal ring 43 so that pressure may be applied to the hanger to anchor or hold it in position. In this manner a seal is formed around the inside of the passage 48 in the hanger so that there can be no escape of pressure. In this manner the hold-down cap 40 can be firmly clamped against the pipe hanger and any desired amount of pressure applied to the packing 15 in order to form a seal inside of the flange 11. This arrangement is of particular

advantage where the hanger does not move down into its seat a sufficient amount so that it is level with the top of the flange 11 as is illustrated in Fig. 2. On the other hand, if the weight of the tubing or pipe 7 is such that the packing 15 5 would be compressed a greater amount, then of course a seal could still be maintained satisfactorily by drawing up on the bolts 32. On the other hand, in event the pipe hanger should be carried by the weight of the pipe to a position 10 below the top of the flange 11, then of course when the cap member 40 were positioned, the bolts 32 would draw the cap downwardly so that the ring 33 would move into the groove 45 and a seal would be provided. In other words, the 15 cap member may fit with either of the rings 33 or 43 or with both of them if circumstances so require.

Broadly the invention contemplates an arrangement of a hold-down cap which can be 20 used to seal with either the hanger or the well head or with both of them simultaneously so that a seal may be provided both through and around the tubing hanger.

What is claimed is:

1. In a well head, a support on the well, a support ring seated therein, a resilient packing thereon, a pipe hanger disposed on said packing and within said support but normally projecting above such support, an annular groove in the top 30 of said hanger, a metal seal ring therein, and a holdown member movable to apply pressure through said ring to maintain a sealing pressure in said packing.

2. In a well head, a support on the well, a support ring seated therein, a resilient packing thereon, a pipe hanger disposed on said packing and within said support but normally projecting above such support, an annular groove in the top of said hanger, a metal seal ring therein, a 40 holdown member movable to apply pressure through said ring to maintain a sealing pressure in said packing, and an additional seal ring on said support to be engaged by said holdown member when said hanger moves downwardly 45 into said support or when there is no hanger in the support.

3. A well head assembly including a head, a blowout preventer thereon, a seat in said preventer, a pipe hanger packing and a pipe hanger 50 on said seat, a seal ring on top of said preventer, a drilling valve on said ring, means on said hanger to receive a seal ring so that a seal may be maintained with either or both said preventer and said hanger when said valve is replaced by a 55 holdown cap.
